UNITED STATES PATENT OFFICE.

HAMILTON WEIR, OF PORTLAND, OREGON.

INHALER.

No. 921,034.

Specification of Letters Patent.

Patented May 11, 1909.

Application filed April 21, 1908. Serial No. 428,351.

To all whom it may concern:

Be it known that I, HAMILTON WEIR, a citizen of the United States, and resident of the city of Portland, in the county of Multnomah and State of Oregon, have invented a new and Improved Inhaler, of which the following is a full, clear, and exact description.

My invention relates to inhalers for medicinal use, the several objects of my improvements being as follows: I. To construct the device mainly of aluminum or other non-corrosive material. II. To connect the various parts without soldering, welding or cementing. III. To enable the parts to be cheaply constructed by stamping, shearing, spinning and analogous processes, whereby the cheapness of production is reduced to a minimum. IV. To give certain metallic parts such form as to enable them to hold securely in position the pads used for the filtration of air or for containing medicines to be inhaled. V. To give the device such a shape as will render it easy of application to the nostrils and will protect the latter from injury thereby. VI. To secure the spring to the truncated cones in an approved manner and to give the spring such form as will increase its general efficiency.

Reference is to be had to the accompanying drawings forming a part of this specification, in which similar characters of reference indicate corresponding parts in all the views.

Figure 1 is a perspective showing the inhaler as used in practice; Fig. 2 shows the device complete, consisting of two truncated cones each fitted internally with a pad, the cones being connected by a U-spring secured thereto as hereinafter described; and Fig. 3 is a vertical section through the mechanism shown in Fig. 2, with the exception that in Fig. 3 one of the pads has been removed.

Two truncated cones 5 made of aluminum or non-corrosive alloy very thin and light, are each provided with a large opening 6, made by cupping the edge of the cone slightly inward and further provided with a smaller opening 7. The edges may be cut by spinning, stamping or punching as desired.

50 A strip 8, integral with the cone 5, is partially severed therefrom by shearing and is then punched inwardly as indicated in Fig. 3, thus leaving upon each cone 5, a strip 9. A bow spring 10, made also of aluminum or

non-corrosive alloy, is substantially of U- 55 shape and its ends are inserted respectively within the two cones and pressed outwardly against the same by the strips 8, the spring thus being in a sense clamped by the strip 8 and the strip 9, as will be understood from 60 Fig. 3. The ends of the spring 10 are further secured by making an indentation 11 in the ends of the spring, these indentations slightly affecting the shape of the strip 8 and raising therein a similar indentation, 12. This enables the strip 8 to grip firmly the end of the U-spring. A pad 13, of absorbent material is mounted in each of the truncated cones, and is used for retaining medicine or absorbing organic matter discharged from the nose or 70 even for the purpose of merely filtering the air used in breathing, as the case may be. These pads are conveniently made of wool woven upon a cotton backing and cut into pieces of proper size and shape. 75

With the apparatus made as above described, the truncated cones may be detached from the U-spring, but are not so easily detached as to readily separate therefrom except when such separation is desired. 80 To all intents and purposes the parts act in practice as if they were integral with each other. If, however, a part be broken, bent or worn out, it may be readily replaced by a similar part. 85

Having thus described my invention, what I claim as new and desire to secure by Letters Patent is:

1. An inhaler comprising a pair of truncated cones, each having its ends open and 90 cupped slightly inward, each cone being provided with slits forming a strip partially severed therefrom, and a U-spring inserted between said strip and the body portion of said cone and clamped therebetween. 95

2. An inhaler comprising a pair of cones of metal, each provided with oppositely arranged and spaced slits forming a strip integral therewith and partially severed therefrom, said strip being held by its ends only to 100 the cone, and a U-shaped spring having a portion inserted intermediate said strip and the body portion of said cone for the purpose of supporting said cone.

3. An inhaler comprising a pair of cones of metal, each provided with two strips integral therewith and partially severed therefrom, one of said strips being pressed inwardly in 105

relation to the other of said strips, and a **U**-shaped member connecting said cones together, said **U**-shaped member having a portion inserted intermediate said strips of each 5 cone.

4. In an inhaler, the combination of a pair of cones of metal, each provided with slits forming a strip integral therewith and partially severed therefrom, said strip having an 10 indentation, and a **U**-shaped member engag-

ing said strip and provided with an indentation mating said indentation of said strip.

In testimony whereof I have signed my name to this specification in the presence of two subscribing witnesses.

HAMILTON WEIR.
